UNITED STATES PATENT OFFICE

136,557

DESIGN FOR A CARPENTER'S BAR

William Charles Scown, Oklahoma City, Okla.

Application August 18, 1943, Serial No. 110,936

Term of patent 14 years

To all whom it may concern:

Be it known that I, William Charles Scown, a citizen of Canada, residing at Oklahoma City, in the county of Oklahoma and State of Oklahoma, have invented a new, original, and ornamental Design for a Carpenter's Bar, of which the following is a specification, reference being had to the accompanying drawing, forming a part thereof.

Figure 1 is a view in elevation of one side of a carpenter's bar embodying the new design;

Figure 2 is a view in edge elevation; and

Figure 3 is a view in elevation of the face of the bar opposite to that illustrated in Figure 1.

I claim:

The ornamental design for a carpenter's bar, as shown.

WILLIAM CHARLES SCOWN.
